DESIGN FOR A SHOE SHINE MACHINE

Glenn Yuille, Pontiac, Mich.

Application October 26, 1948, Serial No. 149,309

Term of patent 3½ years

(Cl. D9—2)

To all whom it may concern:

Be it known that I, Glenn Yuille, a citizen of the United States, residing at Pontiac, Oakland County, Michigan, have invented a new, original, and ornamental Design for a Shoe Shine Machine, of which the following is a specification, reference being had to the accompanying drawings, forming a part thereof, wherein:

Fig. 1 is a front elevation,
Fig. 2 is a top plan view,
Fig. 3 is a left end elevation, and
Fig. 4 is a right end elevation of a shoe shine machine, embodying my new design.

I claim:

The ornamental design for a shoe shine machine, as shown.
